DESIGN FOR AN ELECTRIC SWITCH

Daniel G. Spotts, Batavia, Ill., assignor to William C. Furnas, doing business as Furnas Electric Company, Batavia, Ill.

Application May 31, 1941, Serial No. 101,254

Term of patent 14 years

To all whom it may concern:

Be it known that I, Daniel G. Spotts, a citizen of the United States, residing at Batavia, in the county of Kane and State of Illinois, have invented a new, original, and ornamental Design for an Electric Switch, of which the following is a specification, reference being had to the accompanying drawing, forming part thereof.

In the drawing:

Fig. 1 is a front and side perspective view of an electric switch embodying my new design; and

Fig. 2 is a top plan view of the switch.

I claim:

The ornamental design for an electric switch, substantially as shown.

DANIEL G. SPOTTS.
